UNITED STATES PATENT OFFICE.

MATHEW LEAVY, OF NEW YORK, N. Y.

METHOD OF AND MEANS FOR REFRIGERATING CELLARS AND VAULTS.

SPECIFICATION forming part of Letters Patent No. 356,254, dated January 18, 1887.

Application filed July 13, 1886. Serial No. 207,918. (No model.)

To all whom it may concern:

Be it known that I, MATHEW LEAVY, a citizen of the United States, residing in the city and county of New York, and State of New York, have invented new and useful Improvements in Method of and Means for Refrigerating Cellars and Vaults, of which the following is a specification.

Ordinarily the drip from ice contained in the ice-boxes of bar-rooms and other places escapes by a pipe to the sewer.

The object of my invention is to utilize this waste-drip for the purpose of cooling cellars or vaults for the storage of wines, ales, beers, and other liquors and materials which should be kept in an atmosphere of from 60° Fahrenheit and below.

The object of my invention I accomplish by placing at or adjacent to the ceiling of a cellar or vault or other place a pan or vessel having its bottom portion connected by a pipe or pipes with the ice box or boxes in the bar-room or other place and connecting with such pan above the point where the drip pipe or pipes enter, a coil of pipe traversing a tortuous course in the cellar or vault and discharging into the sewer or other source of escape.

The invention is illustrated by the accompanying drawing, where the figure is a horizontal sectional view through a cellar or vault under a bar-room and partitioned off as usual for the storage of wines, ales, beers, and other liquors, or other materials.

In order to enable those skilled in the art to make and use my invention, I will now describe the same in detail, referring to the drawing, where the dotted lines, indicated by the numeral 1, represent the bar of a saloon or hotel, and 2 the ice-boxes, all located above the cellar. At or adjacent to the ceiling of the cellar or vault is supported in any suitable manner a pan or vessel, 3, which may be closed or open at the top, and from the ice-boxes extend pipes 4, which communicate with the lower portion of the pan—for example, about one inch from the bottom thereof. To the pan at a point above that where the drip-pipes enter—say, for example, six inches thereabove—is connected one end, 5, of a coil of pipe, 6, which traverses a tortuous course through a part of the cellar or vault or other place and connects at its other end with a pipe, 7, leading to a sewer or other place. As the drip-pipes enter the pan below the point of entrance of the end 5 of the coil, there is necessarily

maintained in the bottom of the pan a body of water forming a seal to the drip-pipes and preventing sewer and other gases from rising therethrough to the bar-room, and at the same time such body of water prevents heat from rising through the pan. The drip from the ice-boxes passes by the drip-pipes into the lower portion of the pan, and the waste-water rising therein flows into the coil of pipe and traverses the same, finally escaping through the escape-pipe 7. By thus utilizing the waste water resulting from the melting of ice in the ice-boxes of hotels, saloons, and other places, I am enabled to maintain a cellar or vault or other place having from two to four thousand cubic feet of space at a temperature of from 50° to 55° Fahrenheit with the waste water that melts from four to five hundred pounds of ice for twenty-four hours. The cellar or vault might be in the form of a large storage-box, and the ice-boxes can be in places other than bar-rooms.

Having thus described my invention, what I claim is—

1. The method herein described of utilizing the drip from an ice box or boxes in a bar-room or other place, which consists in carrying the drip-water to a receiving pan or vessel located in a cellar or vault or other place and causing the water to flow from such pan through a pipe traversing a tortuous course in the cellar or vault or other place, and discharging the water therefrom into a sewer or other place of escape, substantially as described.

2. The combination, with the ice-box of a bar-room or other place, of a pan or vessel located in a cellar or vault, a pipe leading from the ice-box to said pan, and a pipe leading from the box and traversing a tortuous course in the cellar or vault or other place, substantially as and for the purpose described.

3. The combination, with the ice-box of a bar-room or other place, of a pan or vessel located in a cellar or vault or other place, a drip-pipe leading from the ice-box to the lower portion of the pan, and a pipe leading from the pan to a point above that where the drip-pipe enters, and traversing a tortuous course through the cellar or vault, substantially as described.

In testimony whereof I affix my signature in presence of two witnesses.

MATHEW LEAVY.
